UNITED STATES PATENT OFFICE

154,752

DESIGN FOR AN EGG BEATER

Alice Yola De Martino, Malverne, N. Y.

Application July 21, 1947, Serial No. 140,415

Term of patent 3½ years

(Cl. D44—1)

To all whom it may concern:

Be it known that I, Alice Yola De Martino, a citizen of the United States, residing at Malverne, Long Island, New York, in the county of Nassau and State of New York, have invented a new, original, and ornamental Design for an Egg Beater, of which the following is a specification, reference being had to the accompanying drawing, forming a part thereof.

In the drawing:

Fig. 1 is a perspective view of an egg beater, showing my new design;

Fig. 2 is a top plan view; and

Fig. 3 is a bottom plan view of the same.

I claim:

The ornamental design for an egg beater, as shown.

ALICE YOLA DE MARTINO.
